MAGNETIC FOCUSING DEVICE

James P. Quam, Chicago, Ill., assignor to Quam-Nichols Company, Chicago, Ill., a corporation of Illinois

Application May 27, 1949, Serial No. 95,731

4 Claims. (Cl. 250—161)

1

This invention relates generally to apparatus for focussing an electron beam such as the beam of a cathode ray tube, and more particularly to a permanent magnet device of this type in which the focussing effect can be adjusted.

In many applications, it is desired to focus a beam of electrons on a particular surface such as on the screen of a cathode ray tube in a television receiver. The focussing device acts on the electron beam in generally the same manner that an optical lens acts on a beam of light rays to cause the beam to converge on a given point or surface. For focussing a beam of electrons, a magnetic field is required in which the lines of flux are parallel to the electron beam. In the prior art, such focussing fields have been produced by electromagnetic coils or solenoids positioned about the beam of electrons. In such devices the current in the coil can be controlled to adjust the field so that the beam is focussed at the desired points.

It has been proposed to use permanent magnet structures for focussing an electron beam. In these structures it is necessary that some means of adjustment be provided to accurately control the field about the electron beam. This may be accomplished by the use of a coil in addition to the permanent magnet with the current of the coil being controlled. Such a structure, however, greatly increases the cost of the unit and is therefore undesirable. It has also been proposed to adjust the air gap of the permanent magnet structure to thereby adjust the strength of the field. While such an arrangement is effective to change the strength of the field, the change in the width of the air gap and the resulting change in the position of the air gap on the tube are objectionable as these factors also affect the focussing and should preferably be fixed at optimum values.

It is, therefore, an object of the present invention to provide an improved permanent magnet device for focussing the beam of a cathode ray tube, in which the strength of the magnetic field can be adjusted without changing the width or position of the air gap.

A further object of this invention is to provide an adjustable permanent magnet focussing device for a cathode ray tube which provides a uniform field of optimum strength about the neck of the tube for focussing the electron beam therein.

A feature of this invention is the provision of a focussing device for a cathode ray tube having magnetic plates with openings therein to receive the neck of the cathode ray tube and defining an air gap about the neck of the tube, with a plurality of permanent magnets between the plates for producing a field at the air gap, and an adjustable crew for shunting the field and thereby varying the strength of the field at the air gap.

2

A further feature of this invention is the provision of a permanent magnet focussing device including pole pieces made of low reluctance material forming an air gap and shunting means for varying the field at the air gap, with the magnets and shunting means being positioned away from the air gap so that the field at the air gap is uniformly distributed therein.

Further objects, features and advantages will be apparent from a consideration of the following description when taken in connection with the accompanying drawings in which:

Fig. 1 illustrates the focussing device in accordance with the invention in an operative position on a cathode ray tube;

Fig. 2 is a front view of the focussing structure; and

Fig. 3 is a side view of the focussing structure.

20 In practicing the invention, there is provided a magnetic structure including a pair of pole pieces made of material having low reluctance with the pole pieces having openings therein and inturned rims. A plurality of permanent magnets are positioned between the pole plates and are firmly secured thereto to provide a rigid overall structure. The inturned rims of the pole pieces provide an air gap across which a magnetic field is produced by the magnets. A screw 30 is threaded in one of the pole pieces and is adjustably positioned with respect to the other pole piece to provide a shunting field between the pole pieces. Adjustment of the shunting screw therefore controls the strength of the field at 35 the air gap. The permanent magnets and the shunting screw are all positioned at the edge of the pole pieces remote from the air gap so that the pole pieces are effective in equalizing the fields of the magnets and provide a uniform field distribution about the air gap.

In Fig. 1, there is illustrated a cathode ray tube 10 having a neck portion 11, and a front face 12 on which may be provided a fluorescent surface 13. The front face 12 and the neck 11 45 may be joined by flared intermediate portion in the usual way. The tube may include a base 14 through which connection is made to the elements within the tube. A socket 15 is shown coupled to the base 14 for making connections 50 to the elements in the tube.

The permanent magnet focus device is indicated generally at 20 and includes pole pieces 21 and 22 having openings 23 therein for receiving the neck 11 of the cathode ray tube. The two 55 pole pieces may be of identical construction. Inturned rims 24 and 25 are provided on the pole pieces and form an air gap 26 therebetween. These annular rims may have restricted or bevelled pole faces 32 which restrict the field and thereby improve the operation of the focussing device. More specifically, a pole face 32 is bevelled, sloped, or slanted inwardly as shown in

Figs. 1 and 3, to restrict or concentrate the field adjacent the tube neck and hence the beam therein. A magnetic field is provided in the air gap by a plurality of magnets 27 spaced about the periphery of the pole pieces 21 and 22. The strength of the field in the air gap can be adjusted by the shunting screw 28 which is illustrated as threaded in pole piece 22. A second air gap is provided between the end 29 of the screw 28 and the pole piece 21 which can be varied to thereby adjust the strength of the field in the air gap 26.

Considering now the operation of the focussing structure, it will be apparent from Fig. 1 that the cathode ray tube includes means for producing a beam of electrons including a heater 35, a cathode 36, and grids 37 and 38. These grids may be of a configuration to cause deflection of the beam so that the ions are removed from the electron stream in a well known manner. The beam of electrons is directed through an opening 39 in the grid 38 and after passing through the opening 39 the stream will tend to diverge as indicated at 40. It is obvious that such a diverging beam would produce a large spot on the screen and this would not be satisfactory in most instances as in a television receiver as it would result in blurring of the picture. The focussing device 20 therefore provides a field in the air gap 26 which acts on the diverging stream of electrons and causes the stream to converge as indicated at 41. The reduction in the size of the spot causes the beam to be concentrated so that the spot produced thereby is very brilliant. The action of the focussing device depends upon the strength of the field in the air gap 26 and therefore the focussing can be controlled by the shunting screw 28 which controls the field in the air gap 26.

As previously stated the field in the air gap 26 is produced by the magnets 27 which are provided between the pole pieces 21 and 22 and which are spaced from the air gap 26. The pole pieces 21 and 22 are made of material having low reluctance so that the field in the air gap will not be concentrated adjacent the magnets but will be substantially uniform throughout the entire air gap 26. The rims 24 and 25 permit spacing the pole pieces at a distance greater than the desired air gap so that longer magnets can be used to provide the magnetic field needed, and the stray fields between the pole pieces are reduced. The strength of the field in the air gap 26 is adjustable by the shunting screw 28 with the flux in the air gap being very small when the end 29 of the screw 28 is adjacent the pole piece 21 and a maximum when the end 29 is at or near the pole piece 22. The shunting screw can be easily made to provide variations of plus or minus 20 percent in the field at the air gap which is considerably more than is necessary for satisfactory operation. Some adjustment has been found necessary as the field required to properly focus the beam of electrons depends upon the particular tube used and upon the voltage used for acceleration of the electron beam.

The focussing device shown is particularly adapted to provide satisfactory focussing of a television receiver. The focussing structure 20 may include lugs 30 for supporting the same on a bracket as indicated at 31 which may be secured to the receiver cabinet or the receiver chassis. An insulating control rod 45 may be secured to the shunting screw 28 for adjusting the position on the screw by a knob 46 at the rear

5 wall 47 of the cabinet of a television receiver or the like. As shown in Fig. 2, the screw 28 has a square recess 49 therein for receiving the insulating rod 45 to thereby insure positive movement of the screw by the rod.

In order to provide satisfactory operation the dimensions of the focussing structure are relatively critical. The following gives the values found most desirable for use in television receivers using cathode ray tubes from 10 to 12 inches in diameter:

Pole pieces 21 and 22:

Outside diameter, $3\frac{1}{2}$ "

Diameter of opening 23, $1\frac{1}{4}$ "

Thickness, $\frac{1}{8}$ "

Width of pole faces, $\frac{1}{4}$ "

Material—cold rolled steel.

Air gap 26 between pole pieces, $\frac{1}{8}$ "

Shunting screw—cold rolled steel, $\frac{1}{2}$ "

Permanent magnets—Alnico #5, $\frac{1}{2}$ " diameter; $\frac{7}{8}$ " long.

It is obvious that certain of these dimensions are interrelated. For example, the diameter and thickness of the pole pieces are related and if a larger diameter is used, the field might be uniformly distributed about the air gap by poles of less thickness (higher reluctance).

Also if less than three magnets are used, the pole pieces would need to be larger and/or thicker to properly distribute the field, whereas if more magnets are used the size of the pole pieces could probably be reduced.

For use with a 10" cathode ray tube a field of the order of 600 gauss is required for providing the proper focus. To provide the required adjustment, the magnetic structure may be magnetized to provide a field at the air gap of about 700 gauss. This field can then be reduced by the adjusting screw to as low as 450 gauss. This obviously provides adequate adjustment for optimum focus. The air gap of $\frac{1}{8}$ " was found to be optimum and only slight tolerance is permitted without reducing the effectiveness of the focusing device. When using magnets $\frac{7}{8}$ " long, the spacing between the pole pieces is approximately three times the width of the air gap so that stray fields between the pole pieces are not objectionable.

The permanent magnet structure described has been found to be very satisfactory in use. The adjusting screw provides the variations in field strength required and does not distort the field. The use of three permanent magnets spaced about the pole pieces provides both a highly satisfactory magnetic field and a very rugged construction. The three magnets provide the field strength necessary in a minimum space and with a small amount of permanent magnet material. The distribution of the magnets in this way provides a very uniform field in the air gap. The use of three magnets provides a three-point connection to the pole pieces which facilitates connection of the magnets and pole pieces to provide a rugged overall structure. The pole pieces can be punched from sheet material with the beveled edges, to provide the restricted pole faces, being machined on a screw machine. The magnets and pole pieces may be secured together by immersion in a solder bath or in any other suitable way. The complete focussing device is smaller and lighter than available electromagnetic focussing devices.

Permanent magnet focussing devices in accordance with the invention are much less ex-

pensive than electromagnet or combined permanent and electromagnet devices. In the first place, the focussing structure itself is less expensive than an equivalent coil. Also, no rheostat or other auxiliary control is necessary for controlling the focussing device. Further, no outside energy is required so that the rectifier in the television receiver or other device in which the device is used need not provide energy for the focussing device. These various factors contribute to make a large overall saving in cost.

While one embodiment of the focussing device in accordance with the invention has been illustrated, it is obvious that various changes and modifications can be made therein without departing from the intended scope of the invention as defined in the appended claims.

I claim:

1. A magnetic structure for focussing a beam of electrons including in combination, a pair of pole pieces, said pole pieces each having a body portion with a beam receiving opening therein, and with said body portions being spaced apart from one another, permanent magnet means extending between said body portions of said pole pieces, said pole pieces each having a part on the inward side thereof at said opening, said parts providing an air gap therebetween having a substantially constant length less than half the spacing between said body portions of said pole pieces, at least one of said parts on said inward side having a bevelled annular edge as a pole face for providing a concentrated field in said air gap, and adjustable means on one of said pole pieces for providing a shunt magnetic path between said pole pieces to adjust the strength of the magnetic field in said annular air gap, said permanent magnet means and said adjustable means being magnetically coupled to said pole pieces and being radially spaced from said body portion openings so that the magnetic field is distributed through said pole pieces and the field in said annular air gap is substantially uniform.

2. A magnetic structure for focussing a beam of electrons including in combination, a pair of pole pieces, said pole pieces each having a body portion with a beam receiving opening therein, and with said body portions being spaced apart from one another, permanent magnet means extending between said body portions of said pole pieces, means for holding said pole pieces and said magnet means in assembled relation, said pole pieces each having a part on the inward side thereof at said opening, said parts providing an air gap therebetween having a substantially constant length of the order of one-third the spacing between said body portions of said pole pieces, at least one of said parts on said inward side having a bevelled annular edge as a pole face for providing a concentrated field in said air gap, and adjustable means on one of said pole pieces for providing a magnetic path between said pole pieces to adjust the strength of the magnetic field in said annular air gap, said permanent magnet means and said adjustable means being magnetically coupled to said pole pieces.

3. A magnetic structure for focussing a beam of electrons including in combination, a pair of pole pieces each having a body portion with a beam receiving opening therein, and with said body portions being spaced apart from one another, permanent magnet means extending between said body portions of said pole pieces, at

least one of said pole pieces having a part on the inward side thereof at said opening which forms an air gap with the other one of said pole pieces having a substantially constant length of less than half the spacing between said body portions of said pole pieces, said part on said inward side having a bevelled annular edge as a pole face sloping inwardly toward the beam receiving opening of said one pole piece for providing a concentrated field in said air gap, and adjustable means on one of said pole pieces for providing a shunt magnetic path between said pole pieces to adjust the strength of the magnetic field in said annular air gap, said permanent magnet means and said adjustable means being magnetically coupled to said pole pieces and being radially spaced from said body portion openings so that the magnetic field is distributed through said pole pieces and the field in said air gap is substantially uniform.

4. A magnetic structure for focussing a beam of electrons including in combination, a pair of pole pieces each having a body portion with a beam receiving opening therein, and with said body portions being spaced apart from one another, permanent magnet means extending between said body portions of said pole pieces, said pole pieces each having a part on the inward side thereof at said opening, said parts providing an air gap therebetween having a substantially constant length which is substantially less than the spacing between said body portions of said pole pieces, said parts on said inward side of said pole pieces each having a bevelled annular edge as a pole face for providing a concentrated field in said air gap, and adjustable means on one of said pole pieces for providing a magnetic path between said pole pieces to adjust the strength of the magnetic field in said annular air gap, said permanent magnet means and said adjustable means being magnetically coupled to said pole pieces.
